UNITED STATES PATENT OFFICE.

GUY MOORE GEST, OF NOROTON, CONNECTICUT.

CABLE-BRACKET.

1,204,858.

Specification of Letters Patent. Patented Nov. 14, 1916.

Application filed October 27, 1913. Serial No. 797,485.

To all whom it may concern:

Be it known that I, GUY MOORE GEST, of Noroton, Connecticut, United States of America, a citizen of the United States of America, have invented certain new and useful Improvements in Cable-Brackets; and I do hereby declare that the following is a full, clear, and exact description of the same.

10 This invention relates to brackets for supporting cables or the like and particularly to those which are located in the manholes of underground conduit systems and are capable of being positioned with relation to 15 and for the support of cables extending from the conduits into the manholes.

One of the objects of the invention is to provide a bracket which is positively held in position by means which are readily accessible and speedily manipulated for securing the bracket in place or releasing the same.

Another object is to provide an easily positioned bracket which is positively sustained under the weight of the cable or cables supported thereby.

Further objects and advantages will be hereinafter more particularly described and pointed out in the claims.

30 For full comprehension, however, of my invention reference must be had to the accompanying drawings forming a part of this specification, in which similar reference characters indicate the same parts and 35 wherein;

Figure 1 is a vertical section taken through the side of a manhole and illustrating the application of my improved bracket to the bracket support, the locking means 40 being loose; Fig. 2 is a similar view illustrating the bracket locked in position; Fig. 3 is a face view drawn to a reduced scale, of the bracket support and bracket; Fig. 4 is a perspective view of the bracket; and 45 Fig. 5 is a similar view of the locking member.

Heretofore the brackets to which this invention particularly relates were each upheld by a bolt located in a vertical slot presented by a member embedded in the side of the manhole and the maintenance of the bolt in position, and therefore the support of the bracket and cable or cables, depended upon the tightening of the bolt head against the 55 slotted member, which support has not been thoroughly satisfactory in use.

To overcome the defects of the former type of bracket I have provided one which is positively sustained under the weight of the cable and I will now describe the same. 60

In the drawings 2 represents the wall of a manhole in which is formed a vertical channel 3 inclosing a bracket support 4 which is flush with the wall and presents a slot 5 disposed longitudinally of and communicates with the channel 3 and within which the bracket is adapted to be inserted all of which is well known and need not be herein described in detail, the function of the slotted bracket support being to permit 70 of the positioning of the bracket relatively to the cable or cables.

In my improved construction the sides of the vertical slot 5 are formed with oppositely disposed notches 6 suitably spaced 75 throughout the length of the slot. The bracket is formed with the usual portion 7 curved for the reception of one or more cables 8 and has a contact face 9 at one end and a member extending outwardly as at 10 80 from the face 9 and upwardly as at 10^a. A lug 11 is formed upon the contact face at both sides of the member or extension 10 and may take the form of webs extending between such extension and the contact face. 85

When hanging the bracket it is brought to the desired position and the extension 10 inserted through the slot 5 into the channel 3, the lugs 11 entering the notches 6, resting upon the bottom thereof and positively holding 90 the bracket against vertical displacement either up or down and thus providing a solid support for the bracket. Accidental withdrawal of the bracket from its support is prevented by a pin 12 which is adapted 95 to be inserted through the slot 5 and rest upon the extension 10 loosely between the portion 10^a of the latter and the inner side of the slotted support 4, the pin being of a length to extend across and beyond the sides 100 of the slot.

To lock the bracket firmly in position I prefer to construct the pin 12 with an arm 13 and to enlarge the middle portion of the pin in one direction to a greater extent than the distance between the inner side of the portion 10^a and the inner side of the support 4, thus forming a cam face 14 jutting out from the main length of the pin. The pin 12 and arm 13 form a member of 110 T-form which is inserted in an obvious manner through the slot 5 to the position shown.

in Fig. 1 and the arm 13 is then moved up and causes the cam face 14 to engage with the portion 10^a and, see Fig. 2, force the pin 12 against the inner side of the support 4 5 and the contact face 9 against the outer face of the latter, the rear of such contact face being braced by the web 9^a therebetween and the curved portion 7. This construction enables the securing means to be located entirely within the channel and not project 10 into the manhole, the arm 13 being readily reached through the slot 5 and forced down to release the bracket.

It is preferred to form the member 10 15 and 10^a in the form of a hook by inclining the inner face of the portion 10^a inwardly from the top as at 15 to co-act with the cam 14 and by inclining and curving the upper surface of the portion 10 while to facilitate 20 the placing of the T-form locking member within the hook and to prevent lateral displacement of such member, the middle portion of the pin 12 is depressed as at 17.

What I claim is as follows:

25 1. In a device for supporting cables and the like, the combination with a bracket support presenting a slot and a notch at the side of the slot and in the front surface of the support, of a member extending from 30 the bracket into said slot, a second member extending from the bracket into and bearing within said notch and means for retaining such members in place.

2. In a device for supporting cables and 35 the like, the combination with a bracket support presenting a slot and notches extending from the sides of the slot, of a bracket, lugs carried by the bracket and located in said notches, an extension upon 40 the bracket and passed through said slot and a pin located between the extension and the slotted support for holding the bracket in position.

3. In a device for supporting cables and 45 the like, the combination with a bracket support presenting a longitudinally disposed slot, of a bracket having an extension passed through said slot, such extension including an upwardly extending portion 50 spaced from the slotted support and a pin located between the upwardly extending portion and the slotted support and disposed transversely of the latter.

55 4. In a device for supporting cables and the like, the combination with a bracket support presenting a vertical slot and notches extending from the sides of the slot, of a bracket, lugs carried by the bracket and located in said notches, an extension 60 upon the bracket and passed through said slot, such extension including an upwardly extending portion spaced from the slotted support and a pin located between the upwardly extending portion and the slotted support.

5. A bracket consisting of a curved portion, a contact face, a brace extending from the curved portion to the rear of the contact face, a hook-like member extending from the contact face and webs extending between 70 the sides of the hook-like member and the contact face.

6. In a device for supporting cables and the like, the combination with a bracket support presenting a vertical slot and notches 75 extending from the sides of the slot, of a bracket, lugs carried by the bracket and located in said notches, an extension upon the bracket and passed through said slot, such extension including an upwardly extending portion spaced from the slotted support and a cam disposed between the upwardly extending portion and the slotted support.

7. In a device for supporting cables and 80 the like, the combination with a bracket support presenting a vertical slot, of a bracket, an extension upon the bracket and passed through said slot, such extension including an upwardly extending portion spaced from 85 the slotted support and a cam disposed between the upwardly extending portion and the slotted support.

8. In a device for supporting cables and the like, the combination with a bracket support presenting a vertical channel and a slot 90 in the front of the support, disposed longitudinally of and in communication with said channel, such slot having notches at the sides thereof, of a bracket presenting a contact face bearing against the front of the support, lugs upon the bearing face and located in said notches, an extension upon the bearing face and passing through the slot into the channel, an upwardly extending portion upon the extension and spaced from the inner side of the front of the support, a pin located between the upward extension and the inner side of the front of the support, a cam face upon said pin adjacent to 100 said upwardly extending portion and an arm upon said pin and adapted to extend through the vertical slot.

9. In a device for supporting cables and the like, the combination with a wall having 110 a vertical channel therein, a bracket support located in the channel, presenting a slot disposed longitudinally of and in communication with the channel and oppositely disposed notches at the sides of the slot and spaced from each other throughout the length of the latter, of a bracket presenting a contact face bearing against the outer side of the support, lugs upon the contact face and located in said notches, an extension upon the contact face between the lugs and extending through the slot into the channel, an upwardly extending portion upon said extension, the inner face of said portion being spaced from the inner side of the sup- 115 120 125 130

port and inclined inwardly from the top thereof, pin adapted to rest upon said extension and lie across the slot in said support, the middle portion of such pin being depressed on one side and enlarged in one direction to a greater extent than the distance between the inner face of said upwardly extending portion and the inner side of the bracket support and an arm upon said pin

5 and adapted to extend through the slot in 10 such bracket support.

In testimony whereof, I have signed my name to this specification, in the presence of two subscribing witnesses.
